UNITED STATES PATENT OFFICE

CLARENCE H. CONANT, OF CHICAGO, ILLINOIS

ELECTRICAL CONNECTER

Application filed June 18, 1926. Serial No. 116,936.

This invention relates to connecters of the type employed for telephone and telegraph lines, and has for its object to provide an insulator which virtually eliminates dissipation of the current to the equipment supporting the conductor.

A further object of the invention is to so construct the insulator that an internal "dry spot" will be had which is proof to rain, dust and other disturbing influences.

A still further object of the novel insulator is to also construct the same as a connector for the handy separation or connection of the conductor in the event of a test or re-pair.

A final but nevertheless important object of the invention is to construct the same of few and simple parts, whereby it may be produced and installed at low expense.

With the above objects in view, and any others which may suggest themselves from the specification and claims to follow, a better understanding of the invention may be gained by reference to the accompanying drawing, in which

Figure 1 is a perspective view of the novel insulator, interposed between fragments of an electrical conductor;

Fig. 2 is a vertically separated view of the insulator;

Fig. 3 is a vertical section thereof;

Fig. 4 is a section on the line 4—4 of Figure 3, and

Fig. 5 is a perspective view of a detail.

Referring specifically to the drawing, 10 denotes the sections of an electrical conductor in which the novel insulator is interposed, these being embedded and soldered into terminals 11 and 12 which meet to form the connection for the conductor sections within the insulator. The terminal 11 is extended with a plug 11a and the terminal 12 with a cavity 12a to receive the plug when the terminals are assembled end-to-end.

The terminal 12 is molded into a bell-shaped housing 13 of a phenolic condensation product or other durable material of high insulating value; and the plug 11 is molded into a circular disk 14 which in abutting an internal shoulder 13a of the housing

forms a bottom closure for the latter except that the rim or bottom wall of the housing is spaced from the periphery of the disk to facilitate the draining of water from the housing when it rains or snows.

To maintain the terminals 11 and 12 in engaged relation, they are fitted with means which co-operate to act as a locking retainer. Thus, the terminal 12 terminates with a short neck 12b which is used as a support for a jack 15, the latter being perforated and pressed upon the neck of the terminal. The jack has medial and terminal flanges 15a and 15b which are apertured at 15c to permit the passage of the plug 11a of the terminal 11, and the apertures have alined extensions 15d to clear a side lug 11b of the terminal plug 11a. The base of the plug 11a is conically enlarged as indicated at 11c to meet the stock of the terminal 11; and the apertures 15c are somewhat out of alinement.

When the terminal 11 is advanced with its plug in the direction of the jack 15, the plug may be inserted like a key, its rounded tip forcing the jack to warp somewhat, owing to the misalinement of the apertures 15c, and therefore to firmly grip the plug; also, when the plug has been fully advanced, its conical base 11c snugly seats in the lower aperture 15c, making a good electrical contact with the jack. The side lug 11b is now above the medial flange 15a of the clip 15, and a twist of the terminal 11 causes the lug to depart from the site of the aperture extensions 15d, and locks the terminals in engaged relation. The departure of the lug occasions the travel thereof over a rise 15e into a pocket 15f, these elements being pressed from the medial flange 15a of the jack. The pocket affords the lug a seat and prevents the return of the lug to disengaging position from vibration or shock.

The insulator also incorporates a safety drain against excess current load. In the housing 13 is embedded a copper ring 16, which spacially surrounds the terminal 12 and the jack 15, tapping off with a conductor 17 to the ground. When the line is overloaded or heavily charged by atmospheric conditions, the excess will jump the gap be-

tween the terminal and the ring and leak off to the ground.

An appliance is thus had which functions as an insulator, a connector, and an over-voltage relief, all in a small and compact article approximating the size indicated in the drawing. The construction of the housing assures the security of the "dry spot" within, the method of fitting the plugs provides an intimate and dependable electrical connection, and the spaced ring furnishes a ready relief in the event of an overcharge. The device is simple and rugged, and is capable of being produced at low cost.

15 While the drawing illustrates the preferred embodiment of the invention, it is possible that various changes and refinements may be made therein, and it is understood that I intend to include such changes and refinements as coming within the scope and spirit of the appended claims.

I claim:—

1. A connector comprising a bell-housing of insulation having a rim, a terminal carried by the housing, a bottom closure for the latter and spaced from the rim thereof, a plug carried by the closure, a yieldable jack for the plug carried by the terminal, and means to lock the plug in the jack, said jack having sections containing slightly staggered plug-receiving perforations conducive to tension of the jack upon the plug.

2. A connector comprising a housing formed of insulating material, a terminal member embedded therein, a substantially tubular jack carried by and extending from said terminal member within the housing, spaced sections carried by said jack and extending laterally from the walls thereof and provided with key-hole slots therethrough with the slot in one section being slightly out of registry with the slot of another section, a contact plug for insertion in said terminal member through the slots of said jack sections whereby to distort said sections for biting contact with said plug, a locking lug on said plug and insertible through said key-hole slots, said plug being rotatable after insertion to dispose said lug over the face of one of said sections, and cooperative means on said plug and jack for locking said plug in position in said terminal.

3. A connector comprising a housing of bell shaped insulating material with an open bottom, a terminal jack embedded in said housing and extending thereinto in spaced relation from the walls thereof, a contact plug insertible in said housing and jack, means for locking said plug in inserted position, said housing having an internal shoulder of reduced diameter surrounding said jack in spaced relation adjacent and inwardly of the housing bottom, and a closure mem-

ber carried by said plug for seating against said shoulder in spaced relation to the bottom wall of said housing.

In testimony whereof I affix my signature.

CLARENCE H. CONANT.
